(57) **CLAIM**

(22) Filed: **Nov. 14, 2008**

The ornamental design for a spray controller, as shown and
described.

(51) LOC (9) Cl. **23-01**

DESCRIPTION

(52) U.S. Cl. **D23/213; D9/448**

FIG. 1 is a top perspective view of a spray controller showing
our new design in an expanded condition;

(58) Field of Classification Search D23/213,
D23/223; 222/182, 402.12; D9/435, 448;
239/589

FIG. 2 is a bottom perspective view thereof;

See application file for complete search history.

FIG. 3 is a front view thereof;

(56) **References Cited**

FIG. 4 is a rear view thereof;
